UNITED STATES PATENT OFFICE.

WILLIAM ZEPP, OF NEW YORK, N. Y.

GAME APPARATUS.

1,158,413.

Specification of Letters Patent.

Patented Oct. 26, 1915.

Application filed April 3, 1915. Serial No. 18,921.

To all whom it may concern:

Be it known that I, WILLIAM ZEPP, a citizen of the United States, residing at the city of New York, borough of Brooklyn, Kings 5 county, in the State of New York, have invented certain new and useful Improvements in Game Apparatus, of which the following is a full, clear, and exact specification.

10 My invention relates to improvements in game apparatus, and the same has for its object more particularly to provide a portable apparatus which is simple, compact in form, conveniently portable, and easy to 15 operate.

Further, said invention has for its object to provide a game apparatus comprising a support, a plurality of spaced partly revolvable buffers, a series of objects to be struck 20 loosely disposed upon the base, and a traveling, rotating striker for overturning said objects.

Further, said invention has for its object to provide an apparatus having a plurality 25 of buffer members each of which comprises a fixed support, a member adapted to rotate partly thereon, and means for limiting the rotation of said revolvable member in either direction when the same is struck by the 30 traveling striker.

Further, said invention has for its object to provide an apparatus in which the rotating striker is adapted to be deflected in an uncertain manner into contact with the 35 buffers so as to cause said striker to be deflected in a plurality of different directions as said striker successively contacts with any certain buffer.

To the attainment of the aforesaid objects 40 and ends, my invention consists in the novel details of construction, and in the combination, connection and arrangement of parts hereinafter more fully described, and then pointed out in the claims.

45 In the accompanying drawings forming part of this specification wherein like numerals of reference indicate like parts,— Figure 1 is a plan or top view showing one form of apparatus constructed according to 50 and embodying my said invention; Fig. 2 is an enlarged section taken on the line 2—2 of Fig. 1; Fig. 3 is an enlarged detail vertical section showing the rotating striker, and the means for supporting and operating 55 the same; Fig. 4 is an enlarged detail side view partly broken away and in section

showing the construction of the buffers, and Fig. 5 is a detail plan or top view thereof.

In said drawings 10 designates the apparatus as a whole comprising a base or table 11, preferably mounted upon legs 12, 12. From the edges of the base 11 extend upwardly wall members 13, 13, and 14 denotes a cover having a rim 15 upon its underside adapted to engage with the inner sides of 65 the wall members 13 adjacent to the upper edges thereof.

Adjacent to each of the corners of the base 11 are provided two buffers 16, 16 which are arranged side by side, and on a 70 line at an angle of about 45 degrees to the side walls 13 of the base or table 11. Each of said buffers comprises a stationary vertical support or rod 17 having a screw-threaded lower end 18 adapted to be secured in the 75 base 11, and an upper reduced portion 19 which is screw-threaded. Upon the upper end of the support 17, and surrounding the threaded end 19 thereof, is disposed a washer 20 which is secured against the 80 shoulder formed at the upper end of the support 17 by a ball or head 21 having an opening therein provided with screw threads adapted to engage with the screw threads upon the reduced end 19 of the support 17. 85

22 denotes a revolvable cylindrical member, preferably made of wood or other suitable material, having an opening extending longitudinally therethrough of such width that the said member 22 may be slipped over the 90 supports 17 and be capable of rotation thereon. At the lower end of the tubular member 22 is provided a plate 23 which is secured to the underside of said tubular member 22 by screws 24. From one side of 95 said plate 23 extends a projection 25 having a segmental slot 26 therein through which extends a pin or stud 27 having its lower end secured in the base 11.

28 denotes a rotating member or top 100 which is provided at the periphery of its body portion with an annular elastic buffer 29 made of rubber or other suitable material. The front wall 13 of the base or table is provided at its center with a cut-out portion 30 to receive the upper and lower ends 105 31^a, 31^b, respectively of the rotating striker 28.

32 denotes a string having one end secured to a handle portion 33, and its other 110 end adapted to be wound upon the lower end of the rotating striker 28. The free

end of the string 32 is adapted to be passed through the opening or cut-out portion 30 provided in the front wall 13.

At about the center of the base 11 are provided suitable indicating marks upon which are loosely disposed pins or other objects 35 to be upset.

To operate the device it merely becomes necessary to insert the rotating striker 28 10 in place at the front wall of the base 11, and after having set the same in rotation by means of the string and handle 33 the said rotating striker will be caused to travel inwardly from the edge of the front wall 15 13, and in the course of its movement strike against certain of the buffers 16. As the annular elastic buffer 29 of the striker 28 contacts with the movable members 22 of said buffers 16 it will cause the said members 22 to be rotated partially, and until one end of the segmental slot 26 in its plate 25 is caused to approach or to engage with the pin or stud 27 when its further movement will be arrested. As soon as this occurs the rotating striker will be deflected away from the buffer and proceed along its path of travel until it meets one of the pins 35 or until it meets another of the buffers 16, and is further deflected.

30 It is to be noted particularly that by reason of the partially rotating nature of the buffers 16, the rotating striker 28 will, as it contacts with the revolute members 22 of said buffers, cause said members 22 to rotate more or less each time the same is struck by the rotating striker. In this way one or the other ends of the segmental slot 26 in the plate 25 will be brought nearer to the pin 27. In this way the succeeding rotation which may be imparted to the member 22, when the same is struck by the traveling striker a second time will be more or less limited. The rotating striker will thus be deflected from each buffer in a somewhat different direction with each successive impact with any one of the said buffers.

Having thus described my said invention, what I claim and desire to secure by Letters Patent is:—

50 1. A game apparatus comprising a base, a plurality of objects to be struck loosely disposed thereon, rotatable buffers mounted upon said base in fixed relation to each other, and a striker adapted to engage said buffers and partially rotate the same, and to contact with said objects to upset the same, substantially as specified.

55 2. A game apparatus comprising a base, a plurality of objects to be struck loosely disposed thereon, buffers mounted upon said base in fixed relation to each other, and ar-

ranged in a plurality of sets disposed at right angles to each other, and a movable striker adapted to engage said buffers, and to contact with said objects to upset the same, substantially as specified.

3. A game apparatus comprising a base, a plurality of objects loosely disposed thereon, buffers arranged in fixed relation upon said base; said buffers each comprising a fixed support and a member loosely mounted thereon, and a movable striker adapted to engage said buffers to be deflected thereby, and to contact with said objects to upset the same, substantially as specified. 75

4. A game apparatus comprising a base, a plurality of objects loosely disposed thereon, buffers arranged in fixed relation upon said base; said buffers each comprising a fixed support, a member mounted to rotate thereon, and means for limiting the extent of rotation of the member mounted upon said support, and a rotating striker adapted to engage with the rotating member on said support, and to contact with said objects, substantially as specified. 80

5. A game apparatus comprising a base, a plurality of objects to be struck loosely disposed thereon, buffers arranged in fixed relation upon said base; said buffers each comprising a fixed support, a tubular member mounted to rotate thereon, a plate extending outwardly from said revolute member and provided with a segmental slot, a stop extending through said slot and into said base for limiting the extent of rotation of said revolute member, and a striker adapted to be projected across said base into engagement with the revolute members on said buffers, and to contact with said objects, substantially as specified. 90

6. A game apparatus comprising a base, wall members extending upwardly from the edges thereof, a plurality of objects to be struck loosely disposed upon said support, buffers arranged upon said base; said buffers each comprising a fixed support, a tubular member mounted to rotate thereon, a plate extending outwardly from said revolute member and provided with a segmental slot, and a stop extending through said slot and into said base for limiting the movement of said revolute member, substantially as specified. 105 110

Signed at the city of New York, in the county and State of New York, this 15th day of January, one thousand nine hundred and fifteen.
